UNITED STATES PATENT OFFICE.

IRIS WINIFRED LEAVER, OF BRIGHTON, ENGLAND.

DESIGN FOR AN EMBLEM OR BADGE OR EMBLEMATICAL DEVICE.

51,343.

Specification for Design.

Patented Oct. 9, 1917.

Application filed July 27, 1917. Serial No. 183,191. Term of patent 3½ years.

To all whom it may concern:

Be it known that I, IRIS WINIFRED LEAVER, a subject of the King of Great Britain, residing at 6 Sillwood Place, Brighton, in the county of Sussex, England, have invented a new, original, and ornamental Design for an Emblem or Badge or Emblematical Device, of which the following is a specification, reference being had to the accompanying drawing, forming a part thereof, the figure showing a front view of an emblem or badge illustrating my new design.

I claim as my invention:—

The ornamental design for an emblem or badge or emblematical device, as shown.

IRIS WINIFRED LEAVER.
